UNITED STATES PATENT OFFICE.

WILHELM MÖLLER, OF HAMBURG, GERMANY.

TUBULAR BOILER.

No. 876,378.

Specification of Letters Patent.

Patented Jan. 14, 1908.

Application filed March 30, 1906. Serial No. 308,885.

To all whom it may concern:

Be it known that I, WILHELM MÖLLER, a citizen of the German Empire, and a resident of Hamburg, Germany, have invented certain new and useful Improvements in Tubular Boilers, of which the following is a specification.

This invention relates to the arrangement of having the upper water chamber or head above the water level of the boiler and the injection of the feed water into the lower water chamber. The steam forming in the upper water chamber when starting to heat the boiler is of higher tension than at other parts and will naturally expand and enter through the upper connecting pipes into the boiler by bubbling from the downwardly directed open ends of upright pipes entering the boiler. The upper chamber completely fills with hot water and a lively circulation is kept up by the constantly rising hot water from the highly heated tubular system.

In order to apply the invention with advantage more particularly to ship's boiler, it is advisable to provide for the easy removal of the water tubes as well as for their instalment in the smallest possible space. For this purpose the vertical water pipes between the two water chambers are curved as portions of a circle. Though curved pipes have been previously used to afford easy removal there is a novel feature in the present arrangement inasmuch as they can be readily and expeditiously removed by disconnecting each one of the covers separately of the water chamber, while in existing systems they can only be removed by opening the water chamber and then pulling the pipes into the interior and then out of said chamber. Obviously the opening and closing of a cover of the water chamber is simpler and less injurious to the boiler than having to open the boiler itself. Ordinary bent water tubes have been mounted at an incline so as to economize space in the height of the structure but my improved system or arrangement insures even greater economy in this direction.

In order that the invention may be clearly understood and readily carried into effect, I will now proceed to describe the same with

reference to the accompanying drawings, in which:

Figure 1 is a top view partly shown in section. Fig. 2 is a rear view with parts removed. Fig. 3 is a side elevation shown partly in section, of the improved arrangement.

The flame-tube boiler is marked *a*, its furnace tubes are marked *b*, the firebars *c*, the fire-bridge *d* and the flame tubes *e*. To the rear of the boiler *a* are secured an upper chamber *f* and a lower chamber *g* connected by a system of curved water tubes *h* as shown. The lower chamber *g* communicates with the lower part of the boiler through pipes *i*, T-pipe *k* and longitudinal pipe *l* which reaches to about the middle of the boiler. The upper chamber *f* is fitted with pipes *m* which lead to T-pipes *n*, and pipes *o*, that enter the boiler and open below the water level *W*.

Externally above the furnace tubes *b* is fixed a deflector bridge *q* of fire bricks serving to direct the flames towards the water pipes *h*. Another bridge *r* of fire bricks is built between the rear plate of the boiler and the upper water chamber *f*.

The generation of steam is more energetically carried out in the pipes *h* than in the boiler *a* and therefore the steam and water has a tendency to flow into the latter. The feed water entering by supply pipes *p p'*, into lower chamber *g* is obliged to pass through the pipes *h* where it is heated and flows with the other water and steam into the boiler *a*. The water thus withdrawn from the water pipe system through the discharge pipes *m*, *n*, *o* is constantly replenished from the water at the lower part of the boiler through the pipes *i* and this energetic circulation greatly expedites the heating of the boiler water.

In Fig. 3 one of the water pipes is shown drawn out as indicated by dash and dot lines. The curved pipes *h* can be withdrawn without hindrance of the deck *S* which is not possible with the straight pipes.

The walls surrounding the sides and back of the water tubes are covered with asbestos or fire clay.

What I claim is:

A boiler having an upper perforated water

chamber above the water level, covers closing said chamber, pipes connecting said chamber with the boiler below the water level, a lower perforated water chamber below the upper water chamber, covers closing said lower chamber, curved pipes connecting the upper and lower chambers and removable through the chamber-perforations, and a

feed water pipe entering the lower chamber, substantially as specified.

Signed by me at Hamburg this 17th day of March 1906.

WILHELM MÖLLER.
